UNITED STATES PATENT OFFICE.

ROBERT ARTHUR MUIR TAYLOR, OF MELBOURNE, VICTORIA, AUSTRALIA.

GAME.

Application filed November 27, 1923. Serial No. 677,291.

To all whom it may concern:

Be it known that I, ROBERT ARTHUR MUIR TAYLOR, a subject of the King of Great Britain, residing at Hotel Windsor, Spring 5 Street, Melbourne, in the State of Victoria and Commonwealth of Australia, have invented an Improved Game, of which the following is a specification.

My improved game, which is primarily 10 intended to be played within doors, but is equally adapted for use in the open air, consists essentially of an inflated toy balloon or balloons of any suitable size and shape, confined within a playing space of any pre- 15 determined size, by means of a net or nets which surround the sides, ends, and top of said playing space. Instead of nets, sheets of canvas or other suitable material may be used to enclose the playing space but I 20 prefer nets. Instead of balloons, other buoyant articles may be used. Extending across the centre of the playing space from one side net to the other is a net similar to a tennis net, across which the balloons or 25 other buoyant articles are hit by the opposing players (who are within the enclosure) either by striking same with the palm of the hand or with a small racket or bat. The balloons or other buoyant articles may be 30 made in the form of a rope quoit, which can be easily grasped by the fingers of the player, and thrown across the net, or hit across it by the palm of the hand of the player, or by means of a small racket or bat. 35 The balloons or other buoyant articles used, which may be of various or variegated colors, or combinations of colors, to add attractiveness, may be strengthened by covering them with a net made of some light ma- 40 terial, and may have advertisements on them. The nets for enclosing the playing space are constructed of either string, cord, twine, tape, jute, hemp, cotton, rug-wool or other suitable material, or a combination of 45 two or more of them, and of any color or colors or combination of colors. Further, the balloons or other buoyant articles, may, if found necessary, be weighted in any ap- 50 proved manner in order to reduce their buoyancy. In playing the game, the object is to hit the balloon or balloons or other buoyant articles across the net to the opposing player or players, each of whom must return the balloon or other buoyant 55 article before it strikes the ground, otherwise he loses a point in the scoring. Owing

to the buoyancy of the balloon or other buoyant article, when hit by a player, it frequently comes into contact either with the bodies of the players or with one of the 60 side nets or the top of the enclosure, and thus causes it to rebound therefrom at all sorts of angles, thus rendering its return, while still in the air, more difficult. The net enclosing the playing space may be made 65 in one piece, or three or five pieces, the latter for preference. When made in more than one piece, the separate pieces are attached to the edges of that portion constituting the top, by means of hooks, or other 70 suitable attachments, so as to hang vertically therefrom. Attached to each of the four corners of the top are cords which are adapted to engage with hooks projecting either from the walls on opposite sides of a 75 room, or other suitable supports, when the game is played in a room, or from oppositely arranged posts or other suitable supports, when played out-of-doors. When such cords are in engagement with said hooks, 80 which are about seven feet or other suitable height from the floor or ground level, the top net is in a horizontal position. If said top net is made integral with its ends and sides, the said ends and sides are turned 85 down so that they extend vertically downwards from the edges of said top. If said ends, or said ends and sides are made separate from the top, they are simply hooked or otherwise attached to the edges of said 90 top, so as to extend vertically downwards therefrom. The net over which the balloons or other buoyant articles are served, is provided with a cord at each top corner 95 thereof, which cords are adapted to engage with hooks projecting either from the walls on opposite sides of a room or other suitable supports, when the game is played in a room, or from oppositely arranged posts or other suitable supports, when played out- 100 of-doors. By this means, the net is kept in position. If preferred, the ends of the cross net may be attached to the side nets. The sides and ends of the nets enclosing the playing space are weighted at their lower 105 ends, or they may be fastened to the floor of a room or the ground in any approved way, so as to be held taut and to prevent the balloons escaping. The top, side, and end nets to enclose the playing space, as well as the net over which the balloons or 110 other buoyant articles are served, may be

decorated with colored tassels or other suitable ornaments and have folly bells or toy bells or tinklers attached to said nets to emit musical sounds as the nets shake during play. When the game is played indoors, suitable narrow openings may be left between the bottom edges of the side or end nets (or both) and the floor, or the top edges of them and the top net, such openings being of sufficient size to allow the balloons to escape into the room when hit by the players. This modification quickens the game, as the escape of a balloon means the loss of a point in scoring. A further modification in the case of the indoor game consists of a second horizontal net parallel with the top horizontal net, and about three feet from the floor. When this second horizontal net is used, the ends of the enclosure are dispensed with, and the balloons are hit over this net and also the cross net. For outside play, the nets constituting the enclosure may be made of wire, so as to better withstand the weather.

Referring to the drawings hereto annexed:—

Figure 1 is a perspective view of a playing space surrounded on both sides, both ends, and also on top, by nets, the side and end nets being detachably connected to the edges of the top net, and a net like a tennis net extending across the centre of the playing space from one side net to the other.

Figure 2 is a plan view of a net for surrounding a playing space, said net being made in one piece, the sides and ends being adapted to be turned down to hang vertically from the edges of the top net, when the latter is suspended in a horizontal position.

Figure 3 is a plan view of nets for surrounding a playing space, the top and two side nets being made in one piece, while the two end nets are separate and adapted to be detachably connected to the edges of the top net.

Figure 4 is a plan view of nets for surrounding a playing space, the top, the two sides, and the two ends being made in separate pieces, the sides and ends being adapted to be detachably connected to the edges of the top net.

Figure 5 is an elevation of the net which

extends midway across the centre of the playing space from one side net to the other. 55 1 is the top net, 2 the end nets, and 3 the side nets. 4 are hooks by means of which said end and side nets are detachably connected to the edges of the top net 1, when not made integral therewith. 5 are cords, 60 one at each of the four corners of the top 1. 6 are hooks projecting from walls or posts or other suitable supports, 7, to which said cords are attached, to hold the top net in a horizontal position. If preferred, instead of having one cord 5 at each of the four corners, there may be two, arranged at right angles to one another, in which case hooks projecting from walls or posts or other suitable supports must be provided, so that the top net may be strained both as regards its length and breadth. 8 is the playing space, and 9 is a net, like a tennis net, which extends across the centre of the playing space from one side net 3 to the other of said nets. 70 10 are cords, one at each end of net 9, and 11 are hooks projecting from walls or posts, or other suitable supports, 12, to which said cords 10 are attached to hold said net 9 in a vertical position. 13 is a balloon within 80 the playing space 8. The meeting edges of the side and end nets may be hooked together to prevent the balloons or other buoyant articles escaping from the playing space. 75

I claim:

1. A game apparatus comprising a buoyant element, a net providing a playing space and confining said element, and a net extending across said space about middle way its length, said buoyant element being adapted 90 to be hit by the players across said net.

2. A game apparatus comprising a buoyant element, a net providing a playing space and confining said element, and a net extending across said space about middle way its 95 length, said buoyant element being adapted to be hit by the players across said net, the first mentioned net including sides, ends and a top and being made in five pieces, the sides and ends being detachably connected 100 to the top, and means for maintaining the sides and ends in taut condition whereby to prevent the escape of the buoyant element from the playing space.

ROBERT ARTHUR MUIR TAYLOR.
